CLAIM

The ornamental design for a medical lamp, as shown and described.

DESCRIPTION

Fig. 1.1 is a perspective view of my design;
Fig. 1.2 is a front view of the design of Fig. 1.1;
Fig. 1.3 is a rear view of the design of Fig. 1.1;
Fig. 1.4 is a right side view of the design of Fig. 1.1;
Fig. 1.5 is a left side view of the design of Fig. 1.1;
Fig. 1.6 is a top view of the design of Fig. 1.1;
Fig. 1.7 is a bottom view of the design of Fig. 1.1;
Fig. 1.8 is a perspective view of a second embodiment;
Fig. 1.9 is a front view of the design of Fig. 1.8;
Fig. 1.10 is a rear view of the design of Fig. 1.8;
Fig. 1.11 is a right side view of the design of Fig. 1.8;
Fig. 1.12 is a left side view of the design of Fig. 1.8;
Fig. 1.13 is a top view of the design of Fig. 1.8;
Fig. 1.14 is a bottom view of the design of Fig. 1.8;
Fig. 1.15 is a perspective view of yet another design;
Fig. 1.16 is a front view of the design of Fig. 1.15;
Fig. 1.17 is a rear view of the design of Fig. 1.15;
Fig. 1.18 is a right side view of the design of Fig. 1.15;
Fig. 1.19 is a left side view of the design of Fig. 1.15;
Fig. 1.20 is a top view of the design of Fig. 1.15;
Fig. 1.21 is a bottom view of the design of Fig. 1.15;
Fig. 1.22 is a perspective view of a fourth embodiment;
Fig. 1.23 is a front view of the design of Fig. 1.22;
Fig. 1.24 is a rear view of the design of Fig. 1.22;
Fig. 1.25 is a right side view of the design of Fig. 1.22;
Fig. 1.26 is a left side view of the design of Fig. 1.22;
Fig. 1.27 is a top view of the design of Fig. 1.22;
Fig. 1.28 is a bottom view of the design of Fig. 1.22;
Fig. 1.29 is a perspective view of yet another design;
Fig. 1.30 is a front view of the design of Fig. 1.29;
Fig. 1.31 is a rear view of the design of Fig. 1.29;
Fig. 1.32 is a right side view of the design of Fig. 1.29;
Fig. 1.33 is a left side view of the design of Fig. 1.29;
Fig. 1.34 is a top view of the design of Fig. 1.29;
Fig. 1.35 is a bottom view of the design of Fig. 1.29.
